Fig. 2

Fig. 3

Fig. 4

FIG. 1 is a perspective view of one embodiment of a vase showing my new design;

FIG. 2 is a perspective view of another embodiment thereof having a nozzle placed between each of the ends of the axe handles;

FIG. 3 is a perspective view of another embodiment of the vase shown in FIG. 1 wherein the axes are turned outwardly and serve as feet; and

FIG. 4 is a perspective view of still another embodiment thereof wherein a nozzle has been placed between the ends of each of the outward turned axe handles.

The undisclosed sides of the various embodiments of the vase are similar in appearance to the sides shown on the drawing.

I claim:

The ornamental design for a vase, as shown and described.
